[57] CLAIM

The ornamental design for a bed pillow with arm rests and cover, as shown and described.

DESCRIPTION

FIG. 1 is a top, front, left side perspective view of the bed pillow with arm rests and cover of the present invention;

FIG. 2 is a rear elevational view of the bed pillow with arm rests and cover of FIG. 1;

FIG. 3 is a left side elevational view of the bed pillow with arm rests and cover of FIG. 1, the right view being a mirror image thereof;

FIG. 4 is a top plan view of the bed pillow with arm rests and cover of FIG. 1; and,

FIG. 5 is a bottom plan view of the bed pillow with arm rests and cover of FIG. 1.
